B. DRAWE

COMBINATION VENT AND SOIL PIPE FITTING

Filed May 5, 1926

FIG. - 1

FIG. - 2

FIG. - 3

By Bates, Macklin, Gorick & Tarr,
Attorneys.

UNITED STATES PATENT OFFICE.

BERNARD DRAWE, OF CLEVELAND, OHIO.

COMBINATION VENT AND SOIL PIPE FITTING.

Application filed May 5, 1926. Serial No. 106,824.

This invention relates to a combination vent and soil pipe fitting so arranged as to provide for the vent pipe crossing the soil pipe. In household and other plumbing 5 there is usually a soil pipe running for more than one story and it is necessary to have vent pipes from the various fixtures leading to a high point on the soil pipe or through the roof. Usually the soil pipe has a maximum 10 outside diameter of six inches and occupies a wall of the bathroom or lavatory which has an internal space of six inches between the laths of opposite sides. Very frequently a medicine chest interrupts the space 15 above the wash stand, so that it is impossible to run a vent pipe from the wash stand upwardly through this space. Inasmuch as a four inch soil pipe is necessary having a minimum external diameter of approximately 20 five inches in the body there is not room enough in a six inch wall to ordinarily extend the vent pipe across the soil pipe.

The result of the conditions mentioned is that heretofore a separate vent pipe has been 25 employed, spaced a sufficient distance laterally from the soil pipe to avoid the medicine chest, or considerable cutting away of the joists was necessary to enable the vent pipe to reach the opposite side of the soil pipe, 30 while in the floor.

My invention is designed to take care of the conditions referred to, and others which arise in practice, by a simplified system of 35 plumbing which I render possible by providing a fitting which has incorporated in it a cross conduit of proper cross-sectional area without increasing the maximum internal width of the fitting or decreasing the soil-pipe passageway. I thus provide a cross 40 over, which may be used within a standard wall having the six inch internal space, and enables a continuous vent stack in available space close to the soil pipe.

By using my cross over, several advantages 45 are obtained, namely, less labor is required in cutting pipe threads and installing the parts, so that the labor cost is reduced; second, less piping and fewer fittings are used, thus reducing the material cost; third, the trouble- 50 some cutting of a floor joist and the consequent weakening of the floor support is avoided as well as the labor heretofore involved in such cutting.

The desired result is accomplished by providing 55 a single integral fitting, which contains the usual vertical discharge space of

four inches in diameter, and has the cross-over in the form of a conduit which embraces the main conduit for approximately one-half its periphery and is intermediately flattened so as not to project beyond the space required for the usual soil pipe socket. The main conduit is bulged forwardly on the side opposite the flattened conduit so as to preserve the proper internal clearance and at 60 the same time increase the available space at the back for the cross conduit. The flattened conduit merges at opposite sides of the soil conduit into cylindrical extensions, which may be threaded to receive the vent pipe on 65 opposite sides. The cross over described is preferably upwardly inclined toward the discharge side to prevent the flattened portion forming any pocket below the bottom line of the intake vent pipe.

My soil pipe fitting in a preferred form, is illustrated in the drawings hereof and is hereinafter more fully described and its essential novel characteristics summarized in 70 the claims.

In the drawings, Fig. 1 is an elevation of the fitting in place within the six inch space in a bathroom wall, the view being taken at right angles to the wall; Fig. 2 is a vertical longitudinal section of the fitting itself at 75 right angles to Fig. 1; Fig. 3 is an approximately horizontal section of the fitting on the offset line 3—3 of Fig. 2; Fig. 4 is a diagram illustrating the old method of piping and the simplified piping by reason of my 80 cross-over.

As shown in Figs. 1, 2 and 3, the body of the soil pipe portion of the combined fitting designated 10 is approximately a cylinder of four inch internal diameter. 11 indicates 85 the usual offset socket at the upper end thereof, adapted to receive the foot of the adjacent soil pipe and having a maximum exterior diameter of substantially six inches. 12 indicates the usual external shoulder at 90 the foot of the fitting.

The cross over conduit is designated 20, it is flattened into the approximate elliptical form shown, being for the most part of much greater vertical extent than lateral and hugging the wall 10 for approximately one-half its circumference. The exterior of the wall 10 in this region constitutes the interior of the cross over conduit. It will be seen that the external wall 21 of the cross over conduit may by this means extend no further 105 from the wall 10 at the back of the pipe,

than the socket member 11, as clearly indicated in Fig. 1.

At opposite sides of the soil pipe proper the vertical elongated passageway 20 gradually merges into cylindrical passageways 23 and 24 coming at opposite sides of the pipe where there is plenty of room within the wall, as shown in Fig. 1.

It will be observed that the cross-sectional area of the vent passageway is approximately the same in all portions of its course; at least, the vertically elongated portion does not reduce the effective area beyond that of the cross-sectional area of the standard pipe threaded into the opening 23 or 24.

Each of the extensions 23 and 24 is preferably internally threaded to receive the pipes leading to the vent stack. I prefer to provide a right hand thread 25 in the intake extension 23 and a left hand thread 26 in the discharge extension 24. This enables the horizontal pipe section connecting the discharge with the stack to be turned into place in this fitting and in this stack T without requiring a union.

It will be observed from Fig. 1 that the socket portion 11 of the soil pipe proper has the usual internal cylindrical opening adapted to receive the ordinary soil pipe section 30 and allow calking space above the shoulder on the foot of that soil pipe length. Also the foot 12 of my fitting is of the standard size to fit within the socket 32 of the usual soil pipe length. Accordingly, my combined fitting is installed in the soil pipe stack in the same manner as an ordinary fitting, and the vent pipes are readily connected, the vent stack being arranged on one side of the soil stack, which enables simple plumbing.

The cross-over conduit 20 has its greatest flattening on the rear face of the pipe midway between the extensions 23 and 24, the top and bottom lines of this conduit being indicated by the dotted lines 27 and 28 in Fig. 2. To prevent the bottom curve 28 from possibly forming a depression or trap, the discharge end 24 is preferably located higher than the intake end 23, so that notwithstanding the curve 28 the conduit never extends below the lowermost point of the intake. Incidentally this upward extension has some advantage in reducing the amount of piping on the intake side and may also increase the space available for the medicine chest.

The diagram of Fig. 4 illustrates the difference between plumbing with my combined fixture and a usual arrangement where one vent stack is employed. In the left hand portion of this view, which represents such old way, A indicates the soil stack, B and C indicate the discharges from the first and second floor toilets into this stack, D and E indicate the discharge from the first and

second floor bathtubs. The pipe D is shown as connected to a pipe F which leads downwardly via the pipe G to the soil stack A below the intake B. The upper end of the pipe F connects to a horizontal pipe H which leads to the main vent stack J, which connects with the soil stack above the highest fixture. The discharge from the first floor wash stand is designated K; it is shown as connected with the pipe G above the entrance of the pipe F for purposes of discharging and for purposes of venting leads upwardly to the pipe H. The second floor wash stand L is shown as connected to pipe M which leads downwardly to the stack A and upwardly to the vent stack J.

The surface of the lowest floor shown is indicated by the line N and the ceiling of the room below by the line P. The cross over in the old system of piping had to be in the region between such floor and ceiling, as shown in the case of the pipe D, and, as the toilet discharge B and its vent J are also located in this region, this usually required at least one joist to be cut short at the top and bottom, practically destroying its supporting value.

Now referring to the right hand half of Fig. 4, the soil stack is indicated by A' and the intake from the two toilets by B' and C'. The main stack is designated J' and in this case is located adjacent the soil pipe on the opposite side from the wash stand instead of being diverted away from the soil pipe beyond the far side of the medicine chests, as in the old method. With my installation the bathtub discharge D' leads directly to the vent stack J'. This vent leads inwardly from above the pipe D' to the toilet discharge B'. The lower wash stand K' has the usual downward discharge G', while the vent pipe H' now leads to my combined fitting, from the other side of which a short pipe H' leads to the stack J'. The second floor bath tub discharge E', wash stand discharge L' and their venting is readily apparent.

Comparison of the two installations will show that by employing my combined section, enabling a cross over within the wall, not only may the vent stack be located closer to the soil pipe thereby reducing the horizontal piping, but a number of elbows and T's and pipe sections are eliminated, all of which makes a decided reduction in the labor of cutting, threading and fitting, while trouble with the floor joists is avoided.

In the diagram S and S' indicate positions of the usual medicine chests above the wash stands K and K'. It will be noticed that the vertical stacks are broken away at this point for condensation in drawing, and plenty of vertical space is available above the pipes H and H'.

While the diagram shows but two floors it

will be readily understood that in an apartment house or hotel for instance where there are a number of bathrooms located in a vertical tier, the saving by my method is correspondingly increased.

Having thus described my invention, I claim:—

1. A combination soil and vent pipe fitting comprising a main pipe section having a socket at its upper end and a transverse pipe embracing the exterior of the main pipe leading from one side of it to the other side beneath said socket, the distance across the transverse pipe and the main pipe section from front to back being no greater than the external diameter of the socket.

2. A combination soil and vent pipe fitting comprising a main pipe section having a socket at its upper end and a transverse pipe embracing the exterior of the main pipe leading from one side of it to the other side beneath said socket, the distance across the transverse pipe and the main pipe section from front to back being no greater than the external diameter of the socket, the transverse conduit being vertically elongated, and merging at opposite sides of the main pipe into cylindrical extensions.

3. A combined soil and vent pipe fitting comprising a single integral casting having a main pipe portion with an internal diameter of substantially four inches and a socket with an external diameter of substantially six inches, and a transverse conduit on the exterior of the main pipe terminating at opposite sides of the main pipe in cylindrical extensions having an internal diameter of approximately two and one-half inches and intermediately vertically elongated so that the total distance from front and back diametrically of the main pipe is substantially six inches.

4. A combined soil and vent pipe fitting comprising a soil pipe portion and a vent pipe portion crossing the soil pipe portion from one side to the other, the wall of the soil pipe adjacent the mid region of the vent pipe being deflected inwardly to accommodate the vent pipe portion and the region of the wall of the soil pipe being deflected

outwardly to preserve the cross section of the passageway of the soil pipe section.

5. A fitting of the character described comprising a main portion and a transverse conduit embracing the main portion and having its passageway vertically elongated back of the main portion, part of the wall of said main portion constituting the inner wall of the transverse conduit, such inner wall being bowed inwardly at the back of the main portion to accommodate the transverse conduit and the front wall of the main portion being bowed outwardly.

6. A fitting of the character described, comprising a single integral casting having a main portion for a soil pipe and a transverse portion for a vent pipe, said transverse portion embracing the soil pipe portion and having its passageway vertically elongated back of the soil pipe, a wall of the soil pipe constituting the inner wall of the vent pipe portion, such inner wall being bowed at the back toward the axis of the soil pipe portion to accommodate the vent pipe portion and the front portion of the soil pipe being bowed away from the axis of the soil pipe substantially correspondingly to preserve the full area of the passageway of the soil pipe.

7. A combined soil and vent pipe fitting comprising a single integral casting having a soil pipe section terminating in a socket, a vent pipe section crossing the soil pipe section, terminating at opposite sides thereof in cylindrical extensions and intermediately vertically elongated to preserve its cross-section while having less radial extent, a wall of the soil pipe section constituting also the inner wall of the vent pipe section and such inner wall being deflected toward the axis of the soil pipe section adjacent the intermediate region of the vent pipe section and the opposite portion of the soil pipe wall being deflected away from the axis of the soil pipe to preserve the full cross-sectional area of the soil pipe passageway.

In testimony whereof, I hereunto affix my signature.
